UNITED STATES PATENT OFFICE.

LOUIS SCHLEY, OF NEW YORK, N. Y.

SASH-FASTENER.

SPECIFICATION forming part of Letters Patent No. 766,395, dated August 2, 1904.

Application filed October 14, 1903. Serial No. 177,014. (No model.)

To all whom it may concern:

Be it known that I, LOUIS SCHLEY, a citizen of the United States, residing at New York, in the county of New York, State of New York, have invented certain new and useful Improvements in Sash-Fasteners; and I do hereby declare the following to be a full, clear, and exact description of the invention, such as will enable others skilled in the art to which it applies to make and use the same.

This invention relates to fasteners for window-sashes; and it has for its object to provide a fastening which may be used for holding the sash at different heights without the use of the ordinary weights and which will serve to hold the sash rigidly against movement in either direction.

A further object of the invention is to provide a construction which may be easily adjusted to permit of raising and lowering of the sashes and which may be held in its inoperative position.

In the drawings forming a portion of this specification, and in which like numerals of reference indicate similar parts in both views, Figure 1 is a view, partly in elevation and partly in section, showing a window frame and sash equipped with the present invention. Fig. 2 is a view, partly in section and partly in elevation, illustrating one of the fastening devices in its inactive position.

Referring now to the drawings, there is shown a window-frame 5, in which is mounted a sash 6, the frame on the inner faces of its sides being provided with metallic racks 7, which racks extend from the top to the bottom of the frame, the racks being arranged between beads 8. Between the beads 8 are engaged the side edges of the sash 6, so that the latter is held against lateral movement in all directions, while it has free vertical movement.

In the bottom rail 9 of the sash are recesses 10, in which are rotatably mounted the cog-wheels 11, which project through the side faces of the sash and engage the racks on the window-frame. Other gear-wheels or cog-wheels, 12, are mounted in the upper portions of the sides of the window-sash and engage also the racks, and as the sash is raised and

lowered all of these cog-wheels rotate, and they form roller-bearings between the sash and the window-frame.

With the above-described construction it will be understood that if one or more of the cog-wheels are held against rotation the sash will be held against sliding movement.

In each of the recesses 10 is a horizontal guideway 13, in which is slidably mounted a locking-pawl 14, which is held normally and yieldably in engagement with the adjacent cog-wheel by means of a helical spring 15, which is disposed between the rear end of the pawl and the corresponding end of the recess. Each of the guideways 13 extend horizontally and then vertically downward, so that the locking-pawl may be moved rearwardly and then downwardly into the lower portion of the guideway, in which latter position it will be held by pressure of its spring 15. When the pawl is raised to the horizontal portion of the guideway, the spring returns it into engagement with its corresponding cog-wheel.

To permit of manipulation of the pawl 14, it is provided with a knob 16, the stem of which works in a slot extending horizontally and then downwardly corresponding to the guideway. The knob projects from the inner face of the window-sash, so that it may be readily grasped and manipulated.

It will be understood that the present fastening provides for securely locking the sash at any point of its vertical movement as well as in wide-open and closed positions.

In practice modifications of the specific construction shown may be made and any suitable materials and proportions may be used for the various parts without departing from the spirit of the invention.

To insure firm engagement of the locking-pawl with the gear-wheel, said gear-wheel has perforations between the teeth. The locking-pawl has a reduced extremity which engages the corresponding perforation.

What is claimed is—

The combination with a window frame and sash, said frame having a rack and the sash having a pinion mounted therein and engaged with the rack, said sash having a recess leading inwardly from the pinion and having its

inner end portion deepened, and having in its front face a slot opening into the recess and corresponding in shape to the recess, of a bolt within the recess and adapted for engagement with the pinion, said bolt being of a size to slidably fit in the outer end portion of the recess and being movable therefrom into the deepened portion of the recess with its engaging end against the outer end wall of the deepened portion, a spring disposed between

the bolt and the inner end of the recess for compression by rearward movement of the bolt, and a handle carried by the bolt and projecting through the slot.

In testimony whereof I affix my signature in presence of two witnesses.

LOUIS SCHLEY.
